2,439,547

APPARATUS FOR PRODUCTION OF
AMMONIUM SULPHATE

Carl Otto, Manhasset, N. Y., assignor to Fuel Refining Corporation, New York, N. Y., a corporation of Delaware

Application March 8, 1944, Serial No. 525,543

1 Claim. (Cl. 23—273)

1

The general object of the present invention is to provide an improved method of, and improved apparatus for converting the ammonia content of distillation gas, and particularly of coke oven gas, into ammonia sulphate by passing the gas through a so-called saturator containing a bath of weak sulphuric acid with which the gas is brought into scrubbing contact, so that ammonia elements in the gas and sulphuric acid elements in the bath liquor combine to form sulphate of ammonia which subsequently crystallizes out of the bath liquor.

A saturator of the character described, comprises a tank which ordinarily has a hopper bottom and the lower portion of which serves as a container for the sulphuric acid bath. The upper portion of the tank space serves as a gas space receiving the gas treated after the latter has been injected into and has risen to and escaped from the upper surface of the bath. Ammonia saturators present special problems rising out of, or increased in importance by, the considerable bulk and gas treating capacity of the saturators. At the level of the top of the bath therein the internal horizontal cross section of such a saturator tank space is usually not less than about eighty square feet and it may be more than three hundred square feet. Ordinarily, the volume of bath liquor in the saturator is in excess of three thousand gallons, and it may be as great as twelve thousand gallons. The volume of distillation gas passing in a twenty-four hour day through a saturator of relatively small size may be as much as twenty million cubic feet, and the daily volume of gas passing through a relatively large saturator may be more than one hundred million cubic feet.

While the bulk of its initial tar content is customarily separated from the gas before the latter is passed into an ammonia saturator, tar is invariably separated from the gas in the saturator at a rate high enough to objectionably affect the saturator operation if the tar is allowed to accumulate in the saturator. The tar accumulation in a saturator can be kept desirably small by providing the saturator with a bath liquor overflow connection and passing bath liquor into the saturator tank more or less continuously so that tar floating on the top of the bath will be carried out of the saturator by the overflowing bath liquor. One object of the present invention is to provide a saturator with an improved overflow connection characterized by the inclusion, in a simple and compact structure, of windows, a cut-off valve, and washing means.

2

In the normal operation of an ammonia saturator, there is invariably a tendency to the deposit on, and rigid adherence to the internal surfaces of the saturator, of dense crystallized ammonia sulphate masses of such physical character that they are commonly referred to as "rock salt." In usual practice the sulphuric acid content of the bath liquor varies from a minimum of three or four per cent up to a maximum of about seven per cent. The tendency to the formation of rock salt deposits is greater when the acidity of the bath liquor is relatively low, as it may be in the production of large ammonia sulphate crystals, than when the acidity is higher, as it customarily is in the production of relatively small crystals. While the rapidity with which rock salt deposits are formed varies with conditions of saturator operation, and may be minimized by washing and other special provisions, it is practically essential in the operation of every saturator to periodically free the saturator from rock salt deposits by the operation commonly known as "killing" the bath.

25 The bath "killing" operation consists in replacing the so-called "mother liquor" of which the saturator bath is composed in normal operation, by a mixture of sulphuric acid and water. The fresh bath liquor formed by said mixture 30 differs from mother liquor in that it does not have the ammonia sulphate content of mother liquor. Normally, the mother liquor holds in solution more than forty per cent by weight of sulphate of ammonia, and in normal operation, 35 mother liquor holds in suspension about thirty per cent by volume of ammonia sulphate crystals. In consequence of their composition differences the density of mother liquor is much greater than that of fresh bath liquor. Thus the 40 density of mother liquor may be about 33 Baumé while the density of the fresh bath liquor may be as low as 22 Baumé.

One object of the present invention is to provide an improved method of, and means for 45 periodically withdrawing mother liquor from the saturator and passing into the saturator sulphuric acid and water, in such manner as to effect the bath killing operation with desirable rapidity and without interfering with the continuous and efficient recovery of ammonia from 50 the distillation gas and so as to minimize the period during which the separation of sulphate of ammonia crystals from the bath liquor at the normal rate is interrupted. A further object 55 of the invention is to effect the bath killing oper-

ation without requiring an increase in bath liquor level height significantly increasing the gas pressure drop in the saturator.

For the attainment of the above mentioned objects, I have provided simple and effective means for storing mother liquor withdrawn from the saturator during the bath killing operation, and for returning the mother liquor to the saturator during a subsequent regular operation period, so that its acid and crystal contents are not wasted. In some cases, more or less of the mother liquor withdrawn during the bath killing operation may be returned to the saturator before the sulphate content of the bath liquor in the saturator has built up to its normal operation value. This permits some reduction in the period required to restore normal operating conditions. In the preferred form of the invention sulphate crystals are separated from the mother liquor withdrawn from the saturator during the bath killing operation prior to the passage of the mother liquor into the storage receptacle in which it is held during the subsequent portion of the bath killing operation.

My improved overflow construction contributes to the attainment of my improved bath killing results. The windows which I provide in the overflow connection permit of easy visual examination of operating conditions in the saturator so that the bath killing operations need not be effected with unnecessary frequency, but may be effected whenever necessary. The cut-off valve which I include in my overflow connection forms a simple and effective means for temporarily interrupting the bath liquor overflow from the bath whenever this may be desirable. Such interruption is sometimes desirable to permit the bath level in the saturator tank to be temporarily raised during a brief portion of the bath killing operation, for the purpose of rapidly removing rocksalt deposits on the inner wall of the saturator tank immediately above the normal bath level. Ordinarily, however, with my invention the entire bath killing and restoring operation may be effected without the significant increase in saturator bath level height which has customarily attended and characterized the bath killing operation practice heretofore followed. Such increase in bath level height objectionably increases the saturator gas pressure drop and the required gas pumping energy.

The various features of novelty which characterize my invention are pointed out with particularity in the claims annexed to and forming a part of this specification. For a better understanding of the invention, however, its advantages, and specific objects attained by its use, reference should be had to the accompanying drawing and descriptive matter in which I have illustrated and described preferred embodiments of the invention.

Of the drawings:

Fig. 1 is a diagrammatic elevation, partly in section, of an ammonia saturator and associated adjuncts;

Fig. 2 is an enlarged elevation through the saturator overflow connection;

Fig. 3 is an inverted plan section on the line 3—3 of Fig. 2; and

Fig. 4 is an elevation of apparatus shown in Fig. 1.

The apparatus shown diagrammatically in Fig. 1, comprises a saturator tank A of conventional type having a cylindrical body, a hopper bottom portion A' and an upper gas outlet A². Coke oven

gas is passed into the saturator through an axially disposed cracker pipe B which receives gas at its upper end from a gas main C through an inlet chamber C' above the saturator. The cracker pipe B comprises a lower end section B' forming an outwardly flared discharge mouth below the normal level A of the bath liquor which fills the lower portion of the saturator and in which the discharge end B' of the cracker pipe is submerged. The bath level A is normally maintained approximately constant by the normally open overflow connection to the saturator including the novel overflow element D hereinafter described.

Bath liquor passing away from the saturator through the overflow element D, passes through a drain pipe E into the receiving or seal chamber F' of a tar separator F. The latter is in the form of a tank open at its upper end to permit tar to be skimmed off the bath liquor in the separator. The latter includes a vertical partition or weir F² separating the lower portion of the chamber F' from a chamber F³ which receives liquor flowing over the weir F² from the chamber F'. An overflow outlet F⁴ from the chamber F³ discharges into a mother liquor reservoir G.

In the normal operation, however, the liquor level in the separator F is kept too low to permit overflow through the outlet F⁴ by a pump H which withdraws liquor from the bottom of the chamber F³ through a pipe connection H' to the inlet of said pump. The pump H has a second inlet pipe connection H² through which the pump may draw liquor from the reservoir G. Flow through the pump inlet connections H' and H² may be cut off or throttled by corresponding valves I and I'. As shown, the pump H has its outlet connected through a heater J to a pipe J' which discharges into a return pot or chamber K through a valve I². The return pot K has a drain pipe or bottom discharge connection K' through which bath liquor passes to the saturator. The drain pipe K¹ extends through the saturator wall and has its lower end extending down into the bath liquor for a few inches.

Crystals formed and settling in the saturator are withdrawn from the bottom of the saturator in an entraining or carrying stream of bath liquor through a crystal outlet passage A³. The latter is connected by a pipe L' to the inlet of a pump L which discharges the carrying liquor and entrained crystals through a pipe L² into a feed tank or receiving chamber M from which most of the larger crystals and a small portion of the carrying liquor pass to a centrifuge N. The bulk of the carrying liquor thus freed from more or less of its crystal content overflows in the tank M through a pipe M'. The latter has a discharge branch including a cut-off valve IG leading to the separator F, a second discharge branch including a cut-off valve IK leading to the return pot K. Liquor passing with crystals from the feed tank M to the centrifuge N, drains from the latter into the return pot K through a drain pipe connection N'. Hot water may be passed into the return pot K through a pipe O including a valve I³ from a water heater or other warm water source P.

Make-up acid is supplied to the saturator continuously or intermittently, through a pipe Q as required to maintain the desired bath liquor acidity, notwithstanding the constant conversion of acid into the sulphate of ammonia. Normally, such a saturator as is shown in Fig. 1 may advantageously include provisions for spraying a

suitable washing liquid against the internal walls of the saturator, such as are disclosed and claimed in my application Serial No. 473,949, filed January 29, 1943, now abandoned. As shown in Fig. 1, a pipe R supplies saturator washing liquid which may come from the hot water source P through a valve I⁴, or through a valve I⁵ from the liquor return pipe J'.

Ordinarily, I consider it advantageous to return some of the bath liquor to the saturator in such manner as to maintain a crystal separation zone immediately above the crystal outlet A³ which serves to minimize or prevent the movement of unduly small crystals to said outlet. The liquor so returned to the saturator may include bath liquor returned from the feed tank M through the pipe M¹, bath liquor which has overflowed from the saturator into the tar separator F, or a mixture of bath liquor from the feed tank and tar separator. Means for maintaining said separation zone are disclosed and claimed in my application Serial No. 492,265, filed June 25, 1943, now Patent No. 2,424,206, issued July 15, 1947. As such means form no part of the present invention and are not necessary to its use, they need not be illustrated or further referred to herein.

As shown, the novel overflow element D, comprises a box-like body serving as a pipe elbow. The flanged inlet end D' of said body is bolted or otherwise rigidly secured to the flanged outer end of a nozzle portion A⁵ of the saturator tank structure. The depending outlet end portion D² of said body is bolted or otherwise rigidly secured through a valve body S to the upper end of the drain pipe E extending down into the tar separator F. The valve body S as shown is an annulus, the central opening S' of which is in register with the bore of the pipe E and with the opening in the outlet end D² of the element D. A butterfly valve member S² is mounted on a horizontal shaft S³ which extends diametrically across the opening S' and has its ends journaled in diametrically opposed portions of the annular member S. Normally, the valve S² occupies its open position shown in full lines in Fig. 2. When rotated into its horizontal position, it prevents significant flow from the saturator through the element D into the drain pipe S³. For its intended use, such small leakage past the valve disc S² as may occur when the latter is in its closed position, is inconsequential.

The element D has vertical side walls each formed with a circular window opening T in which a plate glass disc T' is secured by inner and outer clamping rings T² which are anchored in place by clamping bolts T³. The element D has a vertical wall remote from the saturator tank A and formed with a window opening t closed by a glass window disc t'. The latter as shown is slightly smaller in diameter than the window glasses T. The window glass t' is secured in place by clamping rings T² and clamping bolts T³ similar to those employed to secure the window glasses T in place.

As is well known, saturator surfaces exposed to contact with bath liquor must be formed of or covered by material immune to attack by dilute sulphuric acid. Customarily, the saturator tank is lead lined and the overflow connection may also be lead lined. Ordinarily, however, the element D may well be formed of hard lead, Monel metal or of some other alloy suitably resistant to attack by sulphuric acid. Advantageously and as shown, means are provided for spraying wash liquid into the overflow element D to prevent

deposits of rocksalt in the element and to keep the glass window discs T' and t' suitably transparent. The means shown for this purpose comprise pipes U and UA extending into the element D through its upper side. As shown, the pipe U is connected to a spray head V within the element D. The spray head has three outlets V' so arranged that each outlet discharges a jet of washing liquid directly against a corresponding one of the window discs T' and t'. Wash liquor is supplied to the pipes U and UA through a supply pipe UC which may receive hot water from the source P through a valve I⁶, or may receive warm bath liquor from the pipe J' through a valve I⁷.

In the contemplated operation of the saturator shown in Fig. 1, gas passes continuously through the saturator and in scrubbing contact with the bath liquor therein, so that at all times substantially all of the ammonia elements of the gas are converted into sulphate of ammonia which is dissolved in the bath liquor. While the saturator operation is continuous in respect to the formation of ammonia sulphate, it is intermittent in respect to the composition of the bath liquor, comprising regular operation periods alternating with bath killing and restoring periods.

During each regular operation period, the bath consists of mother liquor. The latter is a dilute solution of sulphuric acid in water and is saturated with dissolved sulphate of ammonia, and holds in suspension a substantial volume of ammonia sulphate crystals of varying sizes. In each regular operation period, bath liquor is returned to the saturator continuously through pipes J' and M' and return pot K at substantially the same rate at which bath liquor is withdrawn from the saturator through the overflow connection and crystal outlet A³. In each regular operation period the composition of the mother liquor will customarily be approximately constant though it may vary slightly, however, if sulphuric acid is not fed through the pipe Q at a rate suitably proportional to the rate at which gas carries ammonia into the saturator. The mother liquor composition may vary also as the saturator temperature changes and thereby increases or decreases the water content of the bath by varying the dew point of the water vapor in the gas.

Each bath killing operation is initiated by valve adjustments required for the passage of mother liquor withdrawn from the bottom of the saturator through the outlet A³ into the storage reservoir G, instead of back into the saturator through the pot K, and for the passage of water into the upper portion of the saturator to replace the mother liquor withdrawn. The valve adjustments then effected in the apparatus shown include the opening of the valves I⁴ and IG, and the closure of the valves I and I' if the latter were previously open. Usually, also the valves I² and I³ should both be then closed. The rate at which water is then passed into the saturator ordinarily should at least equal the rate at which bath liquor is withdrawn from the saturator through the crystal outlet A³. Usually the rate at which water is then supplied to the saturator should be high enough to maintain a small tar eliminating overflow through the outlet A³. In some cases, also, during a brief portion of a bath killing period, the overflow outlet valve S² may be closed and the rate at which water is passed into the saturator made sufficiently higher than the rate at which bath liquor is withdrawn from the saturator to the outlet A³ so that the bath liquor level in the saturator may be raised.

During the bath killing operation, effected as described, the composition of the mother liquor passing out of the saturator to the outlet A³ tends to remain approximately constant since the mother liquor density so greatly exceeds the density of the water passing to the saturator from the heater P that the mother liquor and the water above it do not mix rapidly. The fresh bath liquor formed by the warm water and acid then passing into the saturator, is a good solvent for crystallized ammonia sulphate and rapidly dissolves rock salt deposits on the internal surfaces of the saturator.

The above mentioned increase in the height of bath level in the saturator during the bath killing operation, if and when effected, insures the rapid dissolving of rock salt deposits which may have formed on the saturator wall surface portions adjacent but slightly above the normal bath level. Such deposits may result from the bath liquor turbulence produced by the gas as it is injected into and bubbles up out of the bath liquor and are ordinarily augmented by bath liquor agitating and recirculating provisions. During the bath killing operation, the acidity of the bath may or may not be increased, as conditions make desirable.

After the introduction of sufficient water into the bath to subject the rock salt deposits to a suitable dissolving action, valve adjustments are effected to interrupt the passage of liquor out of the saturator through its outlet and to reduce the rate at which water is supplied to the saturator and to pass bath liquor overflowing into the tar separator into the return pot K instead of into the reservoir G. The inlet valve I' may be opened then or later so that the pump H will gradually pass back into the saturator the mother liquor which accumulated in the reservoir G during the period in which the overflow from the feed tank M passed to said reservoir. Operation in the manner just described is adapted to rapidly effect the bath killing operation and the restoration of the normal ammonia sulphate content of the bath, so that within a few hours following the initiation of the bath killing operation, the normal mother liquor composition of the bath is restored and a new regular operation period is thereby initiated. During the bath killing operation as in regular operation the rate at which make up acid is supplied may be regulated by adjustment of the valve Q' in the acid supply pipe U.

As will be apparent, the reduction in the ammonia sulphate content of the bath occurring on the described replacement of mother liquor by a mixture of water and acid, does not diminish, but, on the contrary, tends to augment the capacity of the bath to absorb ammonia from the gas rise in bath level pumping load. The formation of ammonia sulphate crystals is interrupted, however, when the mother liquor is replaced by the water and acid mixture and is resumed only after the amount of ammonia sulphate in solution in the mixture has materially increased, and the rate at which such crystals are formed does not rise to its normal value until the mixture approaches its saturated solution condition. While the bath killing operation temporarily interrupts the formation of crystals, it does not reduce the total amount of sulphate crystals produced and recovered, but makes their production intermittent.

The rate at which troublesome deposits of rock salt are formed in the saturator depend to some

extent on fortuitous changes in operating conditions and particularly on bath temperature conditions. In consequence, the visual inspection of the interior of the saturator and conditions through a suitable inspection window in the saturator wall or advantageously located in the overflow outlet as are the windows T' and t', permits the bath killing operations to be initiated when, and only when, such operations are needed instead of at regular and unnecessarily frequent time intervals.

Troublesome rock salt deposits are especially apt to occur on the cracker pipe mouthpiece B' and to prevent such deposits, steam or other heating means may be provided for maintaining said mouthpiece at a temperature higher than the average saturator bath temperature. Thus, for example, as shown in Fig. 1, the mouthpiece may be hollow so that it encloses a heating space W of annular form. A valved supply pipe W' supplies steam or other suitable heating fluid to the heating space W and W² represents a valved outlet pipe through which water of condensation or cooled water or air may be discharged from the space W. The rate at which fluid is supplied to the space W may be regulated in accordance with the need therefor as determined by vision inspection through the windows of the element D. In some cases, of course, the flow of heating unit through the heat element may well be continuous. With the apparatus shown in Fig. 1, the amount of tar carried by the mother liquor into the feed tank M and reservoir G, may be kept very small as is practically desirable. In using the tar separator shown in Fig. 1, the tar accumulating in the separator F must be manually skimmed off.

In Fig. 4, however, I have illustrated an overflow receptacle FA differing from the receptacle F of Fig. 1 in that it includes provisions for automatically discharging floating impurities. The receptacle FA includes compartments FA' and FA³ corresponding to the compartments F' and F³ of Fig. 1. However, the compartments FA' and FA³ are shown as separated by a partition FA² which extends upward to a level about the maximum height liquid level in either of the compartments FA' and FA³. Floating impurities in the compartment FA' overflow through an overflow pipe F₅ into tar receiver FB. Bath liquor separating in the compartment FA' from impurities overflowing through F₅ passes into the compartment through an overflow pipe F₆. The latter is open at its lower end to the chamber FA' adjacent the bottom of the latter, and has its upper end discharging into the chamber FA³ through the partition FA² at a level slightly lower than the level at which impurities overflow through the outlet F⁵.

While in accordance with the provisions of the statutes, I have illustrated and described the best forms of embodiment of my invention now known to me, it will be apparent to those skilled in the art that changes may be made in the forms of the apparatus disclosed without departing from the spirit of my invention as set forth in the appended claim, and that in some cases certain features of my invention may be used to advantage without a corresponding use of other features.

Having now described my invention, what I claim as new and desire to secure by Letters Patent is:

Apparatus for producing sulphate of ammonia crystals from distillation gas comprising a satu-

rator tank having a bath liquor overflow outlet opening intermediate its upper and lower ends, conduit means connected to a source of supply of distillation gas and extending into the portion of said tank below the overflow outlet opening for continuously passing distillation gas through said saturator and into scrubbing contact with said bath liquor, an overflow conduit comprising a pipe having one end connected to said tank and communicating with the tank interior through said opening, an outlet chamber member secured to the second end of said pipe and provided with one or more windows through which the interior of said pipe and tank may be inspected, and means for introducing fluid into said chamber member to prevent sulphate crystal deposits on its walls and windows.

CARL OTTO.
